Color photos of selected George Foreman Grills, Applica Consumer Products, Inc; 14 color sheets; All designs made public prior to Jun. 7, 2011.

Primary Examiner — Ricky Pham(74) Attorney, Agent, or Firm — Banner & Witcoff, Ltd.(57) CLAIM

The ornamental design for a grill, as shown and described.

DESCRIPTION

FIG. 1 is a front perspective view of a grill showing my new design;

FIG. 2 is a top view thereof;

FIG. 3 is a bottom view thereof;

FIG. 4 is a rear view thereof;

FIG. 5 is a front view thereof;

FIG. 6 is a right side view thereof; and,

FIG. 7 is a left side view thereof.

The broken line showing of various elements of the grill is for environmental purposes only and forms no part of the claimed design.

1 Claim, 6 Drawing Sheets(56)
